CAN OPENER AND RESHAPER

Andrew H. Withrow, Cincinnati, Ohio

Application April 10, 1946, Serial No. 661,010

2 Claims. (Cl. 7—14.2)

1

This invention relates to can openers and is particularly directed to a type of can opener adapted to remove the entire top of the can and adapted to be revolved around the can for this purpose. The invention is further concerned with an improved method for opening cans.

In view of the more recent developments in the can art, it is now recommended that the housewife leave the contents of the can within the can even after the can has been opened. The can material has now been treated so that it is no longer possible for contamination of the food to occur because of contact with the metal. Accordingly, if the housewife or the user of the canned food product desires to use only a portion of the food contained, the balance may be left in the can for future use and merely stored in the icebox.

As a result of this a problem has arisen as to properly covering the top of the can to prevent the entrance of dust or other foreign matter into the food. In other words, a suitable cover should be maintained over the can and this has not been possible after the can top is removed through the use of the conventional type of can opener.

Therefore, it has been the object of the present inventor to provide an improved can opener and method of opening the can whereby the top of the can is severed around the entire circumference and in such manner as to constitute the removed top portion as a lid for replacement on top of the can for protecting the contents remaining unused as when it is desired to store the same. This objective contemplates appropriate forming of the can top so that it will receive the lid or forming of the lid so that it will fit over the can.

It has been a further object of the present inventor to provide an opener which can be rotated easily for feeding a cutting edge around the can and severing the top portion by cutting through the side just below the top a sufficient distance to provide a rim or circular lip which may be engaged over the can when the removed top is used as a lid.

It has been a still further object to provide a device of this character which will perform all of the operations in one continuous movement, that is to say, will act upon the material of the can deforming it, so that it will later receive the lid portion, at the time of the cutting operation and further, to cause the cutting operation to be effective without the necessity for internal support even though the cut is made slightly spaced down from the flange or bead attaching the original cover of the can.

In conjunction with the above object, the cutting means is designed so that it will have a slicing action in addition to the rolling action which moves it around the can, which slicing action

2

is inherent in the normal rotating means which feeds the can opener.

It has been a still further object of the present inventor to provide means for placing the can opener in position over the circumferential lip at the top of the can and including means for causing a clinching or gripping action holding the opener in position and causing it to feed more readily as its feeding elements are rotated.

10 It has been a still further object of the present inventor to provide a forming roll incorporated in the can opener which will not only taper the upper end of the can but will aid the operation tapering the upper end by indenting the material slightly to decrease the overall diameter of the top of the can and which will leave the lower end of the tapered portion smooth in order that the lid, when inserted over the tapered portion, will engage the smooth portion for a sealed connection.

15 Further objects and advantages of the invention will be more fully apparent from the drawings in which:

20 Figure 1 is a vertical sectional view taken through the opener showing a portion of a can and illustrating the beginning of the operation of severing the top portion of the can.

Figure 2 is a sectional view taken on line 2—2, Figure 1, detailing the gearing and illustrating the eccentric arrangement for clamping the can opener in position for cutting.

Figure 3 is a sectional view taken on line 3—3, Figure 1, illustrating the gripping and feeding rolls.

25 Figure 4 is a general view of the can showing the lid portion severed and the can formed for receiving the lid portion.

Referring to the drawings, the can opener is illustrated in the process of cutting off the top of a can and forming the can to receive the cut-away top which is thereafter used as a lid. The can being opened is indicated at **10** and the lid section at **11**, Figure 4, showing the top fully severed and the upper margin of the can tapered as at **12** for receiving the lid section.

The can opener embodiment disclosed herein includes a body **13** carrying the cutting element **14**, the forming roll **14a** and the gripping rolls **15** and **16**. The cutting element **14** is fixed on the lower end of a shaft **17** by means of a pin **18**. The elements **14a** and **15** are loosely mounted on the shaft. The shaft is journalled in the body **13**, the upper end of the shaft being provided with a shoulder **19** for securing it against downward displacement.

The shaft **17** includes a gear **20** fixed thereto by means of a key **21**, the gear being disposed in a casing section **22** of the body. A downwardly extended boss **23** further journals the shaft **17**, the gripping roll **15** lying against this boss.

A shaft 24 disposed in the body parallel to the shaft 17 carries a gear 25 which is larger than and meshes with the gear 20. This gear 25 is fixed to the shaft by means of a key 26. The lower end of this shaft carries the gripping roll 16 which is disposed adjacent the gripping roll 15 formed on the element 14. These rolls and the cutting and forming elements have an important relationship to the can seam which will be later described in detail.

The shaft 24 is rotated by hand for rotating the cutting element 14 and the roll 16 by means of a handle 27 fixed on the upper end of the shaft by a pin 28. The handle includes a cross member 29 for gripping purposes.

The shaft 24 is directly journaled in a clamping lever 30. This lever includes arms 31-31 straddling the casing portion 22 of the body 13 and a handle extension 32. The handle extension extends outwardly on a plane above the top of the body so as to clear the top of the can and provide working clearance for the hand of the operator. The arms 31-31 may be in separate pieces, one formed on the handle and the other bent downwardly from an attaching flange 33, as at 34, then extending beneath the body 13.

These arms include circular bosses 35-35 extending toward each other in the top and bottom walls of the casing section 22 and journaling the shaft 24. The shaft is eccentrically mounted with respect to the bosses and thus when the handle is swung as shown in dotted lines (Figure 2), the shaft 24 is moved away from the shaft 17.

The purpose of this clamping lever to move the gripping and guiding rolls 15 and 16 close together so as to grip the flange 36 of the can. This flange usually is constituted by a formed portion on the can lid which is crimped over the upper edge of the can body. The margin of the lid is bent upwardly over the can edge and downwardly as shown.

The roll 16 includes a tapered portion 37 providing a lowermost circular edge 38 which engages in the corner 29 of the flange 36. The roll 15 engages the outer wall of the can just beneath the downwardly extended flange portion 40. Thus, when the lever is swung for clamping, the rolls tightly grip the flange and prevent removal or accidental displacement of the opener as well as guiding the opener around the can edge. These elements 15 and 16 are knurled and therefore have a frictional grip on the lip or flange of the can or its adjacent areas which causes feeding of the opener around the can as the handle 27 is rotated.

Thus, the cutting element 14 is rotated and moved around the can wall just below the roll 15. The element includes a circular cutting edge 41 which severs the portion 11 from the can. Beneath this edge is the tapered roll 14a tapering downwardly inwardly from the cutting edge. This tapered roll is loosely mounted on the shaft and forms a tapered portion on the upper end of the can. Accordingly, the lid portion 11 will fit on the tapered portion after complete severance. The tapered portion has sufficient draft so as to receive the flange or rim 43 of the lid portion.

The gear 20 being smaller than the gear 25, the cutting disc element 14 will be rotated at higher speed than the element 16 thus rotatively slicing its way through the can wall. This makes it

possible to cut through without interior support.

The elements 14a and 15 roll loosely on their shaft 17 around the can. A nut engaging a shoulder on the lower end of the shaft 17 holds the roller 14a in position against the cutting element 14. The roller 15 rolls freely between the cutting element and the boss 23 of the body 13.

The forming element 14a includes flutes 14b which are sharp enough to indent (Figure 4) the material of the can slightly so as to decrease the diameter at the top of the tapered can portion. Accordingly the severed lid section 11 may be easily received upon the tapered portion. The flutes taper off to nothing at the lower end of the forming roll so as to maintain an uninterrupted smooth can wall contour at the base of the tapered portion. This prevents leakage between the lid and the can when the lid is in place.

In order to aid in the operation of fastening of the opener on the can, a handle or grip member 44 is rigidly attached to the body 13. This grip member consists of a straight bar extending oppositely to the normal direction of the extension of the handle 32 of the lever 30. The bar includes a screw threaded into the body.

Having described my invention, I claim:

1. A can opener comprising; a supporting body structure, a pair of gripping rolls, said rolls mounted in said supporting structure on parallel axes and substantially adjacent each other, one of the gripping rolls adapted to engage the internal periphery of the end seam of a can and the other adapted to engage the external periphery of the can just below the end seam of the can, means for rotating said gripping rolls, a cutter fixed to the axis of rotation of the external gripping roll and adapted to sever the side wall of the can on a circumferential line below said last-named gripping roll to provide a depending flange for the cap portion, and a forming roll mounted on the cutter axis below the cutter for tapering the upper portion of the can just below the cut so that it will receive the severed lid portion.

2. A can opener comprising; a supporting body structure, a pair of gripping rolls, said rolls mounted in said supporting structure on parallel axes and substantially adjacent each other, one of the gripping rolls adapted to engage the internal periphery of the end seam of a can and the other adapted to engage the external periphery of the can means for rotating said gripping rolls, a cutter fixed to the axis of rotation of the external gripping roll and adapted to sever the side wall of the can on a circumferential line below said last-named gripping roll to provide a depending flange for the severed cap portion, and forming means mounted on the cutter axis adjacent the cutter for tapering the portion of the can adjacent the cut so that the severed lid portion will fit over the open can.
